UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

CAST-STEEL SIDE FRAME.

Application filed May 5, 1925, Serial No. 28,070. Renewed August 8, 1927.

This invention relates to side frames for railway cars and more particularly to specially constructed cast frames having journal boxes and brake hanger brackets 5 integral therewith.

The principal object of my invention, generally considered, is the production of integrally cast side frames in which the various sections of the members thereof are designed 10 so that maximum strength is secured without undue weight in material.

An object of my invention is the provision of a cast side frame for railway car trucks in which the various members thereof are generally 15 T-shape in cross section with webs extending substantially upright, the tension member being formed with a main flange serving as a spring seat at the intermediate portion thereof and extending directly from 20 each end of the spring seat diagonally upward to approximately the upper inner corner of a journal box as an intermediate flange of the diagonal portions of the tension member and joining with the roof of each 25 journal box approximately on line with the face of the inner brass lug.

Another object of my invention is the production of cast side frames for railway car trucks, each frame comprising a compression 30 member, a tension member and bolster column guide members therebetween, all of said members being substantially T or I-shape in cross section, the tension member, however, formed with diagonally disposed 35 end portions and a substantially horizontal intermediate portion, the upper flange of the intermediate portion being bent and continued as an intermediate flange of the diagonal end portions, whereby said end portions may 40 be considered as of + or star section, the bottom flange of the intermediate portion following a line not quite parallel with the intermediate flange to a position near the adjacent journal box where it is curved from 45 the intermediate flange and extended to the journal box side wall joining therewith to take the place of the usual brace.

A further object of my invention is the production of cast side frames for railway 50 car trucks, each frame being formed with a window opening between bolster column guide portions and with triangular openings on opposite sides of the window opening, said triangular openings being framed or 55 surrounded by flanges or ribs tapering in

width or height, the height being greatest from a point slightly above the plane of the journal box roof or the outer corner of the opening to a point downward of the same where the minimum section of the diagonal tension member occurs which is approximately midway of the lower flange surrounding the triangular opening, from which point it decreases in depth gradually along the lower flange portion to the minimum or ordinary flange height and continues so around the remainder of the opening and along the major portion of the upper flange surrounding the opening to a point near the outer corner of the opening where it gradually increases in height and merges with the portion of the flange of maximum height.

A still further object of my invention is the provision of a cast steel side frame for railway car trucks formed with integral 75 journal boxes and brake hanger brackets, said brake hanger brackets being connected to one side of the frame and bracing ribs or webs extending on the opposite side of the frame adjacent the junction of the brake 80 hanger brackets thereto for strengthening the connection of said brackets therewith.

Other objects and advantages of the invention relating to the particular configuration and arrangement of the various parts will 85 become apparent as the description proceeds.

Referring to the drawings illustrating my invention, the scope whereof is pointed out in the claims,

Figure 1 is a side elevation of a cast side 90 frame for railway car trucks embodying my invention, a portion of one end of said side frame being shown in section.

Figure 2 is a plan view of the side frame as in Figure 1, shown partly in section and 95 partly broken away.

Figure 3 is a cross sectional view taken on the line 3-3 of Figure 1 and looking in the direction of the arrows.

Figure 4 is a cross sectional view on the 100 line 4-4 of Figure 1 looking in the direction of the arrows.

Figure 5 is a cross sectional view on the line 5-5 of Figure 1 looking in the direction of the arrows.

Figures 6 and 7 are cross sectional views taken on the correspondingly numbered lines of Figure 5 and looking in the direction of the arrows.

Figures 8, 9 and 10 are cross sectional 110

views taken on the correspondingly numbered lines of Figure 1, the section shown in Figure 10 being taken looking in the direction of the arrows.

5 Referring to the drawings in which similar reference characters designate like parts, there is illustrated a cast side frame 1 which in the embodiment shown comprises a compression member 2, a tension member 3, bolster column guide or strut members 4, integral journal boxes 5 and integral brake hanger brackets 6.

The compression, tension and bolster guide members are preferably formed of generally T or I-shape in cross section, that is, they comprise web portions 7 disposed in substantially upright position and flange portions disposed on opposite sides of the web portions, said flange portions, however, being of different widths and generally tapering in width or depth so that the members are considered more properly T-shaped in cross section rather than I-shaped.

The tension member 3 is formed with an intermediate substantially horizontal portion 8 and diagonally disposed end portions 9 and 10 extending outwardly and upwardly from said intermediate or central portion 8. The diagonal portions 9 and 10 preferably connect with the journal boxes at their outer ends as illustrated most clearly in Figure 1.

The central or intermediate portion 8 of the tension member is formed with a relatively wide upper flange 11 serving as a spring seating portion and preferably provided with spring seat bosses 12. The flange 11 is maintained relatively wide for approximately the full width of the window opening 13 formed between the compression, tension and bolster guide members and beyond said window opening 13 the flange 11 is tapered in width, bent upwardly and continued along the diagonal portions 9 and 10 of the tension member to approximately the upper inner corners of the journal boxes 5, preferably connected with said journal boxes slightly below the normal inner corners thereof and joined with the roofs 14 of the journal boxes at a junction between 50 each and its corresponding inner brass lug 15.

10. The extensions of the upper flange 11 of the tension member along the diagonal end portions of the tension member forms, not 55 the upper flange, but an intermediate flange of said diagonal end portions as the web 7 of the diagonal end portions of the tension member is continued beyond the flange 11 thereof. This makes the diagonal end portions 60 of the tension member generally + or star shape in cross section. Upper flanges 16 are formed along the upper edges of said web 7 serving as the upper flanges of the diagonal end portions of the tension member 65 and also as the lower edge of the triangular

openings 17 and 18 formed on opposite sides of the window opening 13 and framed by the lower flanges 19 of the compression member, the outer flanges 20 of the bolster column members and the upper flanges 16 of the tension member. 70

The lower flange 21 of the tension member extends horizontally for approximately the full width of the window opening 13 beneath the upper flange 11 thereof, and

beneath the upper flange 11 thereof and then is curved upwardly until its direction is slightly convergent with respect to the intermediate flange 11, from which position

Intermediate range 11, from which point it extends substantially straight to approximately the points of contra-flexure corresponding substantially to the location of points 3, 3' of Figure 1, which is at

section line 9-9 of Figure 1, which is at the location of the minimum section of said tension member. From these positions it curves downwardly away from the inter-

curves downwardly away from the intermediate flange 11 and finally connects with a journal box 5 at each end thereof, said flange 21 then extending substantially hori-

zontally and preferably connected with each journal box inner wall at substantially the junction of the lower end of the inner brass tube 15 therewith. The width or depth of

lug 15 therewith. The width or depth of the lower flange 21 of the tension member is substantially uniform and a maximum for approximately the full width of the 95

for approximately the tail width opening 13. From its points 22 where it curves upwardly toward the journal boxes it is decreased in width or tapered to a minimum section of the

maximum width at the minimum section of the tension member adjacent a section corresponding to the line 9-9 of Figure 1 on each diagonal portion of the tension member.

each diagonal portion of the tension member. From these locations the width or depth of the flange 21 increases gradually outwardly until it joins with the journal boxes 5 serv-

The intermediate flange 11 does not vary in width to the same extent as the lower flange 21, the width, however, being grad-

flange 21, the width, however, being gradually decreased from the horizontal spring seating portion thereof where it extends beneath the bolster column portions 4 to form

the relatively wide substantially uniform diagonal end portions of the intermediate flange 11. The ends of these diagonal end portions, however, flare outwardly as they

portions, however, flare outwardly as they join the journal boxes 5. For bracing the flanges 11 and 21 to each other and to the web portion 7, webs 23, most clearly shown

in Figures 1 and 3, are formed between said flanges and web and preferably extend directly beneath the spring seating portions

12. The triangular openings 17 and 18 are
framed by the flanges 16, 19 and 20, the ends
of said flanges being connected at the corners

or said flanges being connected to the sides of the openings by curved portions as illustrated most clearly in Figure 1 and form continuous flanges. These flanges, however, are not uniform in width or depth, the depth

of the flange 16 being a maximum and relatively uniform from approximately the outer corner of each triangular opening, or approximately the position of the section 5 line 2-2 of Figure 1, to positions corresponding to the dotted line 24. From there the depth of the flanges 16 decreases downwardly and inwardly to positions corresponding to the dotted line 25. Likewise the 10 width or depth of the flange 19 decreases from the maximum at the section line 2-2 upwardly and inwardly to positions corresponding to the dotted line 26. Between the positions corresponding to the dotted 15 lines 26 and 25 the remainder of the flanges 19, 20 and 16 framing the triangular openings 17 and 18 is a minimum and substantially uniform in depth or width. By forming these flanges of varying depth or width, 20 as described, a greater efficiency of construction and more uniform strength characteristics are obtained.

For rigidly connecting the outer sides of the journal boxes with the side frame the 25 upper flange 27 of the compression member 2 preferably curves downwardly at its outer ends as shown at 28 and connects at each end with the journal box roof approximately in line with the inner face of the outer brass 30 lug 29. From the point of junction with the corresponding roof 14 the flange is continued as illustrated at 30 to form part of the sloping outer wall of the corresponding journal box. As a further bracing means 35 between the journal box and side frame proper, triangular web portions 31 are preferably provided between the roof of each journal box and the web 7 of the side frame proper.

40 Integral spring hanger brackets 6 are preferably provided integrally connected to the inner portion of the side frame. Said brackets illustrated are generally U-shaped in cross section and are connected to the 45 side frame by having the web portion of the U sloped upwardly and connected with the upper flange 27 of the compression member 2 as shown most clearly in Figure 3. The flanges 32 and 33 of the U preferably extend 50 in substantially vertical planes, said flange 33 connecting directly with the lower flange or bead 19 of the compression member and the flange 32 being bent angularly at its lower end toward said bead for connection 55 therewith as shown at 34. Reinforcing webs or flanges 35 preferably connect the flanges or beads 16-19-20 framing the triangular openings 17 and 18 with the junctions between the lower horizontal flange of the 60 compression member and the bolster guide portions or flanges 36 and 37. It will be noted that said webs 35 also serve to reinforce the junction between the brake hanger brackets and the side frame.

From a consideration of Figure 1 it will 65 be apparent that the bolster column guiding flanges or web portion 36 and 37 are spaced closer than the lower portions of the bolster column guides or struts 4 so that the bolster may be conveniently inserted at the 70 lower portion of the window opening 13 and then moved upwardly to position as is usual.

The compression member 2 is preferably 75 of generally lighter section than the tension member 3 because it is called upon to bear less stress than the tension member. The inner portions of all of said flanges are preferably formed thinner than the corresponding outer portions thereof. The reason for such construction is that truck 80 side frames of this type are generally cast with the outer or front portion in the cope or upper side of the mold so that when metal is poured into the mold the rear flange or rear portions of the flanges of the side 85 frame are formed first and as the pouring is continued the metal rises until finally the front flanges or portions of the flanges are formed. Unless provision is made to take care of the differences in quality between 90 the metal forming the front and rear portions of the flanges by increasing the thickness of the front portions, it will be obvious that the rear portions will have greater 95 strength. This would result when the side frame was in service in stressing the outer portions of the flanges to a greater degree in proportion to their strength than the inner portions.

By providing, as above pointed out, flanges 100 of unequal thicknesses at inner and outer portions thereof, this defect has been obviated so that the side frame will have flanges of uniform strength. Of course if the side frame were cast in the opposite way with the inner or back portion of the flanges in the cope side of the mold the difference between the thicknesses would be reversed, those portions formed in the cope side of the 105 mold always preferably being heavier than those formed in the lower or drag side thereof.

In view of the foregoing it will be seen 110 that I provide an improved integral side frame which is preferably formed of cast steel with the journal boxes and brake hanger brackets preferably, but not necessarily, integrally united therewith. The various members are formed with tapering flanges 115 or webs, or both where desirable, so that great efficiency in design is obtained, that is, the compression member is formed with a fairly uniform web but with an upper flange 120 which gradually decreases slightly in width or depth to near the junctions with the journal boxes where it flares outwardly slightly. The lower flange of the compression member 125 is preferably of uniform width above the

window opening 13, those portions, however, above the triangular openings 17 and 18 being partly tapered as heretofore described.

The flanges of the bolster column or strut 5 members 4 are preferably substantially uniform in width or depth although they are thickened at their sides adjacent the bolster 10 guide or web portions 36 and 37 as illustrated. The tension member is formed with 15 a main flange 8 which is abnormally wide or deep at the spring seating portion under the window opening 13 where it serves as a top flange of the tension member, from which 20 position it is tapered or decreased in width 25 to form a relatively wide intermediate flange for the diagonal end portions of the tension member. Said intermediate flange, however, flares slightly at its ends where it connects with the journal boxes. The lower flange of 25 the tension member is relatively wide beneath the window opening 13, although not as wide as the spring seating portion, from which it gradually decreases in width or tapers to the minimum sections of the tension member 30 corresponding to the position of the section line 9—9. From these positions it flares outwardly and joins with the journal boxes.

The web 7 of the tension member is generally of tapered formation along the diagonal end portions thereof, outwardly from 35 the junctions with the intermediate portion 8, decreasing in width to approximately the points of contra-flexure and from there increasing in width to the junctions with the 40 journal boxes. The upper flange 16 tapers or decreases in width inwardly and downwardly along an intermediate portion thereof, the ends of said flange being substantially uniform but each end being of a different depth or width.

From a consideration of Figure 8 it will be apparent that the upper flange of the compression member is very much wider than the lower flange whereas in considering Figure 9 it will be seen that the intermediate flange of the tension member is very much wider than either the upper or lower flange thereof.

The foregoing features are particularly 50 pointed out because they result in very desirable strength characteristics in the finished side frame. One of the important reasons why such desirable strength characteristics are secured in a finished side frame, 55 constructed in accordance with my invention, is that such a frame does not have inherent tendencies to induce strains in the edges of the section due to unequal shrinkage after casting. It has been found that with a side 60 frame, the members of which are channel shape in cross section, such members are not balanced with respect to the neutral axis; that is, there is more metal to one side of the 65 neutral axis than to the other side. When the metal cools in such a section, there is a

tendency for it to bow out of line. In a cast truss, such as a side frame, the members are held in rigid relation, so that they cannot freely bow out of line, but the effort to do so sets up shrinkage strains, which are believed to cause many of the early failures of channel section frames. With a member of star or I section there is an approximate balance between the metal on both sides of the neutral axis so that shrinkage strains are 75 greatly reduced.

Having thus described my invention, I claim:

1. A car truck side frame comprising a compression member, a tension member, bolster guide columns interposed between intermediate portions of said members, said members being generally T-shape in cross-section, journal boxes at the ends of said frame and formed with brass lugs, said tension member being formed at its intermediate portion with an upper flange serving as a spring seat, said flange being continued diagonally upward to opposite sides of said spring seat as an intermediate main flange of the tension member and joining with the journal box roof in line with the face of the inner brass lug. 80

2. A car truck side frame comprising a compression member, a tension member, bolster guide columns interposed between intermediate portions of said members, said members being generally T-shape in cross-section, journal boxes at the ends of said frame and formed with brass lugs, said tension member being formed at its intermediate portion with an upper flange serving as a spring seat, said flange being tapered beyond the spring seat and extended diagonally upward from the ends of said spring seat to near the upper inner corners of the journal boxes, and joining at each end with the roof of a journal box in substantially the plane of the face of the inner brass lug. 90

3. A car truck side frame comprising a compression member, a tension member, bolster guide columns interposed between intermediate portions of said members, said members being generally T-shape in cross-section, journal boxes at the ends of said frame and formed with brass lugs, said tension member being formed at its intermediate portion with an upper flange serving as a spring seat, said flange being decreased in width beyond the spring seat and extended diagonally upward therefrom under the bolster guide columns as an intermediate flange between the upper and lower flanges of the tension member and uniting with the journal boxes below the normal upper inner corners thereof, joining the roof of each box at substantially the junction of the inner brass lug therewith. 10

4. A car truck side frame comprising a tension member formed with an intermediate 11

- substantially horizontal portion and end portions extending diagonally upward from the ends of said intermediate portion, all of said portions being formed with substantially 5 vertical web portions and upper and lower flanges on opposite sides of the web portions, the upper flange of the intermediate portion being extended as an intermediate flange of the diagonal end portions.
- 10 5. A car truck side frame comprising a tension member formed with an intermediate substantially horizontal portion and end portions extending diagonally upward from the ends of said intermediate portion, all of said 15 portions being formed with substantially vertical web portions and upper and lower flanges on opposite sides of the web portions, the upper flange of the intermediate portion serving as a spring seat and being decreased 20 in width at the ends of the intermediate portion and continued as an intermediate flange of the diagonal end portions, with outer flanges above and below the same.
6. A car truck side frame comprising a 25 tension member formed with an intermediate substantially horizontal portion and end portions extending diagonally upward from the ends of said intermediate portion, all of said portions being formed with substantially 30 vertical web portions and upper and lower flanges on opposite sides of the web portions, the upper flange of the intermediate portion being relatively wide to serve as a spring seat and gradually decreased in width and 35 bent upwardly adjacent the junctions of the intermediate and end portions and extended along the diagonal end portions as an intermediate relatively wide flange, the lower flange being gradually decreased in width 40 from the junctions of the intermediate and end portions to intermediate portions of the diagonal end portions and from there increased in width to the ends of the tension member.
- 45 7. A car truck side frame comprising a tension member formed with an intermediate substantially horizontal portion and end portions extending diagonally upward from the ends of said intermediate portion, all of said 50 portions being formed with substantially vertical web portions and upper and lower flanges on opposite sides of the web portions, journal boxes at the ends of the diagonal portions of the tension member, the upper flange 55 of the intermediate portion of the tension member being continued as an intermediate flange of the diagonal end portions and connecting with the journal boxes, the lower flange of the intermediate portion being 60 continued as the lower flange of the end portions, following lines sloping toward the intermediate flange to near the journal boxes where it is curved away from said intermediate flange and joins the journal boxes to 65 act as a brace.
8. A car truck side frame comprising a tension member formed with an intermediate substantially horizontal portion and end portions extending diagonally upward from the ends of said intermediate portion, all of said 70 portions being formed with substantially vertical web portions and upper and lower flanges on opposite sides of the web portions, journal boxes at the ends of the diagonal portions of the tension member, the upper flange of the intermediate portion of the tension member being continued as an intermediate flange of the diagonal end portions and connecting with the journal boxes, the lower flange of the intermediate portion being 75 continued as the lower flange of the end portions, said lower flange gradually decreasing in width to intermediate portions of the diagonal portions, from where it is increased in width and joins with the journal boxes at its ends.
9. A car truck side frame comprising a tension member formed with an intermediate substantially horizontal portion and end portions extending diagonally upward from the ends of said intermediate portion, all of said 80 portions being formed with substantially vertical web portions and upper and lower flanges on opposite sides of the web portions, journal boxes at the ends of the diagonal portions of the tension member, the upper flange of the intermediate portion of the tension member being continued as an intermediate flange of the diagonal end portions and connecting with the journal boxes, the lower flange of the intermediate portion being 85 continued as the lower flange of the end portions, said lower flange gradually decreasing in width to intermediate portions of the diagonal portions, from where it is increased in width and joins with the journal boxes at its ends.
10. A car truck side frame comprising a tension member formed with an intermediate substantially horizontal portion and end portions extending diagonally upward from the ends of said intermediate portion, all of said 90 portions being formed with substantially vertical web portions and upper and lower flanges on opposite sides of the web portions, journal boxes at the ends of the diagonal portions of the tension member, the upper flange of the intermediate portion of the tension member being continued as an intermediate flange of the diagonal end portions and connecting with the journal boxes, the lower flange of the intermediate portion being 95 continued as the lower flange of the end portions, said lower flange gradually decreasing in width and sloping toward the intermediate flange to intermediate portions 100 of the diagonal ends of the tension member, where it is curved away from said intermediate flange, gradually increased in width and joined with the journal boxes at its ends.
- 110
11. A car truck side frame comprising a tension member formed with an intermediate substantially horizontal portion and end portions extending diagonally upward from the ends of said intermediate portion, all of said 115 portions being formed with substantially vertical web portions and upper and lower flanges on opposite sides of the web portions, journal boxes at the ends of the diagonal portions of the tension member, the upper flange of the intermediate portion of the tension member being continued as an intermediate flange of the diagonal end portions and connecting with the journal boxes, the lower flange of the intermediate portion being 120 continued as the lower flange of the end portions, said lower flange gradually decreasing in width and sloping toward the intermediate flange to intermediate portions 125 of the diagonal ends of the tension member.
- 130

where it is curved away from said intermediate flange, gradually increased in width and joined with the journal boxes at its ends to act as a brace, the union between said 5 lower flange and the journal boxes being effected at substantially the juncture between the lower ends of the inner brass lugs and the journal box walls.

11. A car truck side frame comprising a 10 compression member, a tension member and bolster guide members interposed between intermediate portions thereof, forming triangular openings adjacent the ends of the compression and tension members, said members being formed with upright web portions with a flange on each edge thereof, the lower, upper and outer flanges of the compression, tension and bolster guide members, respectively, being united at rounded corners to 15 form a continuous flange framing each triangular opening, said flanges being of maximum height adjacent the outer corners of the openings, the height thereof gradually decreasing therefrom.

12. A car truck side frame comprising a 20 compression member, a tension member and bolster guide members interposed between intermediate portions thereof, forming triangular openings adjacent the ends of the compression and tension members, said members being formed with upright web portions with a flange on each edge thereof, the lower, upper and outer flanges of the compression, tension and bolster guide members, respectively, being united at rounded corners to 25 form a continuous flange framing each triangular opening, said flanges being of maximum height for a distance from approximately the outer corners of the triangular 30 openings for a substantial distance along the upper portion of the tension member and gradually decreasing in height from each end of said portion for substantial distances to 35 form flanges of minimum height extending 40 the remainder of the distance around the openings.

13. A car truck side frame comprising a 45 compression member, a tension member and bolster guide members interposed between intermediate portions thereof, forming triangular openings adjacent the ends of the compression and tension members, said members being formed with upright web portions with a flange on each edge thereof, the lower, upper and outer flanges of the compression, tension and bolster guide members, respectively, being united at rounded corners to 50 form a continuous flange framing each triangular opening, said flanges being of a substantially-uniform, relatively great height for a distance from approximately the outer corners of the triangular openings approximately to the midportions of the tension member flanges bordering the openings, 55 tapering in height from there for approxi-

mately the remainder of said tension member flanges and tapering in height from the outer corners of the triangular openings along the compression member for approximately the same distance as that of the other 70 tapered portions, the remainder of the flanges joining the ends of the tapered portions being of a substantially-uniform, relatively small height.

14. A car truck side frame comprising a 75 compression member, a tension member, bolster guide columns interposed between intermediate portions of said members, sail members being generally T-shaped in cross section and formed with substantially upright web portions and flanges on opposite edges of said web portions, the lower, upper and inner flanges on the compression, tension and bolster column members, respectively, framing a window opening, and triangular openings formed on opposite sides of said window opening and framed by portions of the lower, upper and outer flanges of the compression, tension and bolster column members, respectively, the flanges framing the upper portions of said openings being joined by a bracing web extending between each upper corner of the window opening and the adjacent portion of the flange framing a triangular opening.

15. A car truck side frame comprising a compression member generally T-shaped in cross section with a substantially continuous upper flange and a lower flange formed in three parts, the intermediate part forming 100 the upper portion of a window opening and the outer parts forming the upper portions of triangular openings on opposite sides of the window opening, and web members joining said portions of said lower flange 105 and each extending between an upper corner of the window opening and an adjacent corner of a triangular opening.

16. A car truck side frame comprising a compression member, a tension member, bolster guide columns interposed between intermediate portions of said members, said compression member being formed with upper and lower flanges on opposite edges of a substantially upright web portion, said lower 110 flange being formed as a central portion between bolster guide columns and end portions on the outer sides of said bolster guide columns, brake hanger brackets joined to said compression member adjacent the upper portions of the bolster column guides and connected to one side of the web of the compression member and the adjacent flanged portions thereof, and web portions extending between the adjacent lower flanged portions 115 of the compression member on the opposite side of the web portion for bracing the connection of said brake hanger brackets with the truck side frame.

17. A car truck side frame comprising a 120

- compression member, a tension member, bolster guide columns interposed between intermediate portions of said members forming a substantially central window opening between 5 compression, tension and bolster guide members, and triangular openings on opposite sides of the window opening between said members, all of said openings being framed by adjacent flanges on said members, 10 brake hanger brackets integrally connected with said frame adjacent the junctions between the bolster column guides and the compression member to one side of said compression member, and web portions extending 15 on the opposite side of said compression member adjacent the junctions of the brake hanger brackets therewith for bracing the connection with said brackets, said webs extending from the flange at the upper corners 20 of the window opening to the adjacent portions of the flanges framing the triangular openings.
18. A car truck side frame comprising a tension member formed with an intermediate substantially horizontal portion and end portions extending diagonally upward from the ends of said intermediate portion, all of said portions being formed with upright webs, said intermediate portion being formed 30 with upper and lower flanges on opposite edges of its web with the upper flange extended as an intermediate flange of the diagonal end portions, said diagonal end portions being formed with upper and lower flanges 35 on opposite edges of the webs thereof whereby the intermediate portion of the tension member has two flanges and the diagonal extending end portions have three flanges:
- 40 19. A car truck side frame comprising a tension member formed with an intermediate substantially horizontal portion and end portions extending diagonally upward from the ends of said intermediate portion to unite 45 with journal boxes on opposite ends of the frame, all of said portions being formed with substantially vertical webs, the intermediate portion comprising upper and lower flanges and the end portions comprising relatively narrow upper and lower flanges and a relatively wide intermediate flange, said intermediate and lower flanges on the end portions extending as continuations 50 of the upper and lower flange of the intermediate portion and joining at the outer ends with the journal boxes.
- 55 20. A car truck side frame comprising a tension member formed with an intermediate substantially horizontal portion and end portions extending diagonally upward from the ends of said intermediate portion, all of said portions being formed with substantially vertical webs, the intermediate portion having upper and lower flanges and the end 60 portions having upper, lower and intermediate flanges, the intermediate flange being relatively wide and fairly uniform in width, the upper flange increasing in width toward its outer end and the lower flange increasing in width from an intermediate portion toward both ends thereof. 70
21. A truck side frame comprising compression, tension and bolster guide members, journal boxes at the ends of the frame, said tension member being formed intermediate 75 its ends with an upper flange extending substantially horizontally, said flange being continued diagonally upward from said horizontal portion as a flange positioned intermediate the upper and lower edges of the tension member and joining with a journal box at each end thereof. 80
22. A truck side frame comprising a compression member, a tension member and bolster guide columns interposed between intermediate portions of said members, leaving openings adjacent the ends of the compression and tension members, said members comprising upright web portions flanged on either edge thereof, the adjacent flanges of the compression, tension and bolster guide members joining to form a continuous flange around each opening, said flanges being varied in strength in accordance with the varying stresses to which the sections are 90 subjected. 95
23. A truck side frame comprising a tension member formed with an intermediate substantially horizontal portion and end portions extending diagonally upward from the ends of said intermediate portion, all of said portions being formed with upright webs, the intermediate portion having upper and lower flanges and the end portions having in addition an intermediate flange. 100 105
24. A truck side frame comprising a tension member, the intermediate portion of which is approximately horizontal and the end portions of which extend diagonally upward from the ends of the intermediate portion, all of said portions having a substantially upright web, the intermediate portion being flanged at its upper and lower edges and the end portions having upper, lower and intermediate flanges, the intermediate flange being substantially wider than the upper and lower flanges. 110 115
25. A truck side frame comprising a tension member formed with an intermediate substantially horizontal portion with a substantially vertical web and upper and lower flanges, end portions extending diagonally upward from the intermediate portion, said end portions being generally star shape in cross section with the metal on opposite sides of the neutral axis substantially balanced whereby shrinkage strains are reduced. 120 125
- In testimony whereof I affix my signature.
